C. H. SHERMAN

BRACELET

Filed June 24, 1922

Inventor

Chas. H. Sherman,

By Lester L. Sargent

Attorney

UNITED STATES PATENT OFFICE.

CHARLES H. SHERMAN, OF NORTH ATTLEBORO, MASSACHUSETTS.

BRACELET.

Application filed June 24, 1922. Serial No. 570,741.

To all whom it may concern:

Be it known that I, CHARLES H. SHERMAN, a citizen of the United States, and a resident of North Attleboro, in the county of Bristol 5 and State of Massachusetts, have invented new and useful Bracelets, of which the following is a specification.

The object of my invention is to provide a bracelet consisting of a novel combination 10 of elements, and to provide novel means for loosely securing said plurality of bracelet elements, as by one or several bands of metal or other suitable material. I attain these and other objects of my invention by the de- 15 vices illustrated in the accompanying drawings, in which—

Figure 1 is an enlarged elevational view of my bracelet in use;

Fig. 2 is a side elevation of my bracelet, 20 partly in section;

Fig. 3 is an enlarged sectional view on line 3—3 of Fig. 1;

Fig. 4 is an enlarged detail longitudinal 25 section of a portion of the bracelet, includ- ing the clasp pin 6;

Fig. 5 is an end elevation of a modified form of my invention; and

Fig. 6 is an enlarged section on line 6—6 of Fig. 5.

30 Like characters of reference indicate like parts in each of the several views.

Referring to the accompanying drawings, I provide suitable metal bracelet strands 1, which may be either ornamental or plain, 35 and suitable bead bracelet members 2 consisting of a flexible wire 3 on which the beads are mounted. The term "bead" as herein used shall be construed to apply to any approximately equivalent element such 40 as a small cylindrical shell threaded on the wire 3. I provide a suitable cylindrical shell 5 through which the free ends of the flexible wire 3 are inserted in opposite directions and the ends of said wires each looped about 45 the other wire at the end of the shell 5, as shown in Fig. 4.

My complete bracelet consists of a suitable combination of bracelet elements 2 and bracelet strands 1, preferably arranged alter- 50 nately as shown in either Fig. 1 or in Fig. 5, and suitably held together loosely by some suitable securing means 6, such as the metal

band shown in Fig. 5, said metal band having its free ends 7 brought into contact as shown in Figs. 3 and 6. This band prefer- 55 ably substantially conceals the cylindrical shell 5 and also performs a useful function in holding the bracelet members together and adds also to the beauty of the ornament as a whole.

It is within the contemplation of my in- 60 vention to provide any suitable arrangement of the beads on the wire strand, in like colors and sizes, or in alternating colors and sizes or in other combinations. It is also within 65 the contemplation of my invention to suitably fasten the wires 3 together, either in the manner illustrated, which is my preferred form, or in the manner disclosed in my co- 70 pending application Ser. 553,277.

What I claim is:

1. A bracelet of the class described having in combination metal bracelet strands, bead bracelet members, said bead bracelet mem- 75 bers consisting of beads strung on a flexible wire, the aforesaid strands and bead bracelet members being alternately arranged, and means for binding the aforesaid strands and bracelet members loosely together at a given point.

2. In a bracelet of the class described, the combination of a plurality of bead bracelet and metal strand bracelet members, the bead bracelet members being arranged alternately relative to the metal strand bracelet mem- 85 bers, the bead bracelets consisting of beads strung on a flexible wire, a cylindrical shell through which the ends of the wire are in- 90 serted, the ends of the wire being looped one to the other at the ends of the shell, and means for binding the several bracelet ele- 90 ments loosely together at a predetermined point.

3. In a bracelet of the class described, the combination of a plurality of bead bracelets and metal strands, the bead bracelets comprising a flexible wire on which the beads are strung, and having the ends of said wire looped together, a small cylindrical shell through which said wire is threaded near 100 its ends, and a metal binding element loosely engaging the several bracelet elements to hold same in proximity.

CHARLES H. SHERMAN.
